DESIGN FOR AN ASHTRAY

Florence Rose Green, London, England

Application September 30, 1936, Serial No. 65,079

Term of patent 7 years

To all whom it may concern:

Be it known that I, Florence Rose Green, a subject of the King of Great Britain and Ireland, residing at Furnival House, 14 High Holborn, London, England, have invented a new, original, and ornamental Design for Ashtrays, of which the following is a specification, reference being had to the accompanying drawing, forming part thereof.

I claim:

The ornamental design for an ashtray, as shown.

FLORENCE ROSE GREEN.
